(57) **CLAIM**

The ornamental design for a food temperature collection, storage and retrieval system, as shown and described.

DESCRIPTION

FIG. 1 is an isometric illustration of a food temperature collection, storage and retrieval system of the present invention.

FIG. 2 is a front view of the food temperature collection, storage and retrieval system.

FIG. 3 is a rear view of the food temperature collection, storage and retrieval system.

FIG. 4 is a top view of the food temperature collection, storage and retrieval system.

FIG. 5 is a bottom view of the food temperature collection, storage and retrieval system.

FIG. 6 is a left side view of the food temperature collection, storage and retrieval system; and,

FIG. 7 is a right side view of the food temperature collection, storage and retrieval system.

The broken line showing of structural features is included for the purpose of illustrating non-claimed subject matter and forms no part of the claimed design.
